UNITED STATES PATENT OFFICE

ROSCOE C. BOSWELL, OF NEW HARTFORD, NEW YORK

PICTURE HANGER

Application filed October 27, 1927. Serial No. 229,135.

This invention relates to picture hangers and has for its object to provide an attachment adapted to be secured at the back of a picture with a free end formed thereon in the nature of a hook by means of which the picture may be suspended from a wall hook or fastener secured to the wall.

A further object is to form the attachment from a single piece of material thereby enabling the manufacture of the same at a relatively low cost, which is neat and attractive in appearance, embodying sufficient strength to securely support the picture, and otherwise well adapted for the purposes for which the same is intended.

Other objects and advantages reside in the special construction and arrangement of the features forming the invention as more fully hereinafter described and claimed, reference being had to the accompanying drawings forming part hereof, wherein like numerals refer to like parts throughout the specification and in which

Figure 1 is a perspective view showing the hanger secured to the back of a picture in supporting position,

Figure 2 is a similar view showing the wall hook attaching end disposed at a relatively low position to enable the picture to hide the wall hook and

Figure 3 is a perspective view of a modified form of hanger.

Referring to the drawings in detail, the invention comprises a picture hanger indicated at 5 of a generally T-shaped formation, preferably constructed of a suitable thin light weight metal, and adapted to have its transversely disposed section 6 arranged near the upper edge at the back of a picture 7 and secured thereto by screws 8.

The longitudinal section of the hanger extends downwardly along the back of the picture with the end thereof opposite from the transverse section 6 bent upwardly as at 9 and inclined outwardly from the picture. The end 9 is provided with a longitudinally extending slotted opening 10 within which a wall hook 11 may be inserted whereby to suspend the picture therefrom.

The bend forming the end 9 may occur at

any point along the longitudinal portion of the hanger and when arranged near the end thereof will substantially shorten the length of the end 9 whereby upon attaching the hanger to the hook 11 the latter will be entirely hidden from view by the picture.

Figure 3 of the drawings represents a modified form of the invention showing the manner in which the hanger may be formed from a single strand of wire, the ends of the wire being formed into eyes 12 for receiving picture attaching screws, the wire being shaped substantially similar to the hanger 5, with its intermediate section bent upwardly to form an attaching member 13 for engaging the wall hook 11.

It is obvious that the invention is susceptible of various changes and modifications without departing from the spirit thereof or the scope of the appended claim, and I accordingly claim all such forms of the invention to which I am entitled.

I claim:

A picture hanger, a substantially T-shaped frame, an attaching member of bendable material having its laterally disposed ends at the head of the member secured to the frame and its lower end free and adapted to be turned upwardly and outwardly with respect to the picture frame at a predetermined point intermediate its ends, said free end being open between its side edges whereby to receive a picture supporting hook.

In testimony whereof I affix my signature.

ROSCOE C. BOSWELL.
